Attorney.

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed November 16, 1921. Serial No. 515,437.

To all whom it may concern:

Be it known that I, JESSE A. B. SMITH, a citizen of the United States, residing in Stamford, in the county of Fairfield and 5 State of Connecticut, have invented certain new and useful Improvements in Type-writing Machines, of which the following is a specification.

The present invention relates to sound-10 deadening casings in which typewriting machines are adapted to be operated.

Such a casing usually has a window-pane, through which the operator may observe the printing. It has been found that light, 15 either artificial or natural, may, in certain positions of the casing, be objectionably reflected by the window-pane to the eyes of the operator.

One feature of the present invention is 20 the provision of means whereby the window-pane may be shaded from any light which would otherwise strike the same at an objectionable angle. It is undesirable that such a shade should obstruct the vision 25 of the operator or render the work-sheet too dark to read and so, in the preferred embodiment of the invention, the shade or light-deflector is of translucent or light-diffusing material, such as ground glass 30 or glass of roughened or uneven surface, and is positioned behind the line of vision of the platen.

A feature of the invention is a pivotal mounting of the shade or blinder, whereby 35 the same may be swung forward to any position for interception of undesirable light-rays; and a means whereby the shade or blinder may be automatically secured in any adjusted position thereof. In the 40 embodiment of the invention hereinafter specifically shown, the shade or blinder is in the form of a glass plate carried by arms, of spring sheet-material, which exert a lateral pressure on their supports on the casing-cover, and which, by the friction thus 45 created, hold the shade in the position in which it is turned on its pivotal mounting.

Other features and advantages will hereinafter appear.

50 In the accompanying drawings,

Figure 1 is a view in side elevation, partly in cross-section, of a casing embodying the attachments of the present invention; the casing being partly broken away to in-

dicate the typewriting machine, and to show 55 certain connections, therein.

Figure 2 is a perspective view of the light-reflector carried by the cover, and of the brackets on which the same is pivoted.

Referring to the drawings, the casing is 60 shown as comprising a body-portion 1, and a cover-portion 2 hinged to the body-portion. The body-portion is provided with a suitable lining and the cover with a similar lining as indicated at 5. The position of the platen is indicated in dotted lines at 8 (Figure 1), on the carriage of the typewriting machine, part of the typewriter frame being shown at 9; the keyboard extension 10 of the typewriting machine protruding through a suitable opening in the front wall 11 of the body-portion of the casing. A slot 12, which extends horizontally lengthwise of the front wall of the casing-cover, is normally closed by yieldable cushions (not shown). Through this slot protrude levers (not shown), including the line-space lever, which are all mounted upon the typewriter carriage and which move along the slot 12 between the 70 yieldable body-cushions which form the same, as the carriage of the typewriting machine has its letter-feed and return movements.

In the top of the cover 2 is a window, 85 through which the operator may observe the printing platen 8. The window comprises a frame 44, in which is seated and suitably held a pane 45 of glass or other transparent material. When artificial light 90 or daylight strikes the pane 45 at certain angles, an objectionable reflection may be thrown into the eyes of the operator. To prevent light from striking the pane 45 at such angles as to cause such objectionable 95 reflection, there is provided a shade or blinder in the form of a plate 46, preferably of ground glass, or of glass having an uneven surface, but which, in any event, is of such material as to diffuse the light 100 which would otherwise strike the pane at an objectionable angle; without, however, darkening the work-sheet to render it unreadable.

The plate 46 is intended to be adjustable 105 not only between operative and inoperative positions, but between different operative positions, according to lighting conditions.

Accordingly (see Figure 2), it is shown as held at each end in U-shaped metal pieces 48, secured to or forming part of arms 49, having pivot-holes 50 at one end thereof. 5 The holes 50 serve to receive pins 51 on brackets 52, screwed or otherwise secured to the cover at the sides of the window. The arms 49 are preferably spring-arms, the tendency of which is to press outward 10 against the inside faces 53 of the brackets 52, so that the plate 46, when rocked to any desired position, will be maintained in that position by the friction of the arms 49 on the faces 53 of the brackets. The holes 50 15 are of sufficient size to accommodate the spring action of the arms. In Figure 1, an operative position of the shade 46 is shown in full lines; and another position, which may be the normal and an inoperative 20 position, is shown at 54 in dotted lines.

Variations may be resorted to within the scope of the invention, and portions of the improvements may be used without others.

Having thus described my invention, I 25 claim:

1. The combination with a typewriting machine, comprising a platen upon which a work-sheet is typed, of a sound-deadening casing for said machine, said casing having 30 a work-sheet illuminating opening in front of the platen, through which the typing upon the enclosed work-sheet is visible to the operator, a transparent pane in said opening, said pane capable of reflecting surface glare from the exterior source of work-sheet illuminating light, and translucent light-diffusing means mounted to occupy a position out of the line of vision of the operator and between said pane and the source 35 40 of light, for overcoming the glare, said light diffusing means leaving the enclosed work-sheet visible through said transparent pane.

2. The combination with a typewriting machine, comprising a platen upon which a work-sheet is typed, of a sound-deadening casing for said machine, said casing having a work-sheet illuminating opening in front of the platen, through which the typing upon the enclosed work-sheet is visible to the operator, a transparent pane in said opening, said pane capable of reflecting surface glare from the exterior source of work-sheet illuminating light, and translucent light-diffusing means mounted to occupy a position out of the line of vision of the operator and between said pane and the source of light, for overcoming the glare, said means leaving the enclosed work-sheet visible 45 50 55 60 65 through said transparent pane and comprising a device for diffusing the light.

3. The combination with a typewriting machine, comprising a platen upon which a work-sheet is typed, of a sound-deadening casing for said machine, said casing hav-

ing a work-sheet illuminating opening in front of the platen through which the typing upon the enclosed work-sheet is visible to the operator, a transparent pane in said opening, said pane capable of reflecting surface glare from the exterior source of work-sheet illuminating light, and translucent light-diffusing means mounted to occupy a position out of the line of vision of the operator and between said pane and the source of light, for overcoming the glare, said means leaving the enclosed work-sheet visible through said transparent pane, and being adjustable to compensate for different positions of the machine relatively to the sound-deadening casing and to the source of light. 70 75 80

4. The combination with a typewriting machine, comprising a platen upon which a work-sheet is typed, of a sound-deadening casing for said machine, said casing having a work-sheet illuminating opening in front of the platen, through which the typing upon the enclosed work-sheet is visible to the operator, a transparent pane in said opening, said pane capable of reflecting surface glare from the exterior source of work-sheet illuminating light, and means mounted to occupy a position out of the line of vision of the operator and between said pane and the source of light, for overcoming the glare, said means leaving the enclosed work-sheet visible through said transparent pane and in the form of a translucent shade mounted for pivotal adjustment on said sound-deadening casing. 90 95 100

5. The combination with a typewriting machine, comprising a platen upon which a work-sheet is typed, of a sound-deadening casing for said machine, said casing having a work-sheet illuminating opening in front of the platen, through which the typing upon the enclosed work-sheet is visible to the operator, a transparent pane in said opening, said pane capable of reflecting surface glare from the exterior source of work-sheet illuminating light, and means mounted to occupy a position out of the line of vision of the operator and between said pane and the source of light, for overcoming the glare, said means leaving the enclosed work-sheet visible through said transparent pane, and comprising a translucent pane extending the length of said opening, a frame for supporting said pane, and a pivotal adjustment for said frame upon said sound-proof casing. 105 110 115 120

6. A sound-deadening casing for a typewriting machine, having a window through which the operator may observe the printing, a transparent pane for the window, a shade or blinder for intercepting light rays upon which would otherwise be reflected by the pane to the eyes of the operator, and arms for supporting the shade or blinder; 125 130

the arms being pivoted to the casing, and being of spring material to exert a lateral pressure against their supports, whereby the shade or blinder may be held by friction in any adjusted position.

7. A sound-deadening casing for a type-writing machine, having a window through which the operator may observe the printing, a transparent pane for the window, and
- 10 a shade or blinder of translucent or light-diffusing material, such, as for instance, as ground glass, or glass of uneven surface, for intercepting light rays which would otherwise be reflected by the pane to the
- 15 operator's eyes.

8. The combination with a typewriting

machine, of a sound-deadening casing therefor having a window to illuminate the enclosed work-sheet and through which the operator may observe the printing, a transparent pane for the window, and a translucent shade or light-diffusing means movable from a normally ineffective position to an adjustment wherein it intercepts incoming light rays which would otherwise be reflected by the pane to the operator's eyes.
